UNITED STATES PATENT OFFICE.

ROBERT E. EINSTEIN, OF ST. LOUIS, MISSOURI.

RAILWAY-FROG.

No. 857,930.

Specification of Letters Patent.

Patented June 25, 1907.

Application filed August 6, 1906. Serial No. 329,448.

To all whom it may concern:

Be it known that I, ROBERT E. EINSTEIN, a citizen of the United States, residing at St. Louis, Missouri, have invented a certain new and useful Improvement in Railway-Frogs, of which the following is a full, clear, and exact description, such as will enable others skilled in the art to which it appertains to make and use the same, reference being had to the accompanying drawings, forming part of this specification, in which—

Figure 1 is a plan view of a railway frog embodying the features of my invention, one of the guard members being in section; Fig. 2 is a cross sectional view taken on the line 2—2 of Fig. 1; Fig. 3 is a cross sectional view taken on the line 3—3 of Fig. 1; Fig. 4 is a view similar to Fig. 3 showing a shallow T-rail used as the guard member; and Fig. 5 is a view similar to Fig. 3 showing a deep T-rail used as the guard member.

This invention relates to railway track structures, and particularly to railway frogs having a guard member attached to or combined with the frog proper for guiding the wheel flange past the point of the frog by means of a tread rim contact in a horizontal plane above the top surface of the frog.

The main object of my invention is to cheapen the construction and increase the efficiency of this class of frogs.

Another object is to provide a guard member which can be used with the railway frogs that are in general use and also be capable of being applied to said frogs after they have been installed.

Another object of my invention is to provide a guard member which is so constructed that by changing the position of same after it has become worn the engaging face of same will be brought closer to the running line of the frog and thus compensate for wear, thereby enabling said member to be used for an extended period.

Another object of my invention is to provide a guard member of regular shape and form which after becoming worn at one end can be interchanged with the guard member at the opposite side of the frog with which it is used or a different frog of the same angle and thus bring into commission the opposite end of the guard member which has been subjected to very little wear. And still another object of my invention is to provide means for preventing the frog or the rolling stock from receiving a sudden shock as the wheel

enters the frog, this being accomplished by so constructing the guard member that the tread rim of the wheel engages the same gradually.

Referring to Fig. 1 of the drawings which represent the preferred form of my invention, 1 designates the point of the frog, 2 and 3 the wing rails of the frog, and 4 a filler, the parts above referred to being of ordinary construction. Arranged adjacent the wing rails 2 and 3 are guard members 5 and 6 which extend above the tread faces of the heads of said rails, as shown in Fig. 2, said guard members extending over the heads of said wing rails for a portion of their length adjacent the point of the frog, as shown in Fig. 1, so that the rim of the tread of the car wheel 7 will engage the vertical face of the head of said guard member, thereby guiding the wheel flange past the point of the frog. Said guard members each consist of a central straight portion and flared end portions E which extend at an angle to said central portion, the guard members being so arranged with relation to the frog that one of the flared end portions of each guard member extends parallel to the adjacent face of the point of the frog. The central portion of the guard members diverge slightly from the wing rails 2 and 3 and are held spaced away from same by fillers 8. The guard members are preferably held by bolts 9 passing through them and through the fillers and rails which constitute the frog but if desired, the guard members can be retained by means of clamps or by attaching said members to plates placed under the frog.

In Fig. 1 I have shown the guard member as consisting of a casting provided with suitable strengthening ribs, said casting comprising a head 10, a web, and a base 11. If desired, however, I can use a T-tail 12 or rolled section of suitable shape to act as the guard member, as shown in Figs. 4 and 5, Fig. 4 illustrating the way in which I utilize a shallow T-rail for the guard member, which consists in mounting it on a block 13 fastened to a plate 14 that is placed underneath the frog. If desired, I can use a casting of suitable form provided with an engaging face of relatively harder material than the other members of the frog.

When in operative position the head of one of the flared ends of each guard member projects over the head of its co-operating wing rail and the base of said guard member pro-

jects over the base of the rail, thereby aiding in securing the wing rails to the cross ties. The guard members may be secured to the cross ties by spikes 15 which engage the bases thereof, as shown at the lower portion of Fig. 1, or, if desired, laterally projecting extensions 16 can be formed integral with the base of the guide member and be provided with openings to receive the fastening spikes as shown at the upper portion of Fig. 1.

The openings in the web of the guard member through which the retaining bolts 9 pass are similarly located at both ends of the guard member and are formed equi-distant from each other, and as the guard member is of regular form and both ends are of the same shape it can be interchanged with the guard member on the opposite side of the frog with which it is used or a different frog of the same angle and thus bring the end which has received practically no wear into position adjacent the point 1 of the frog where the abrasion is greatest. Said guide members are also provided with additional sets of bolt holes 17, as shown in Fig. 1 so that when a guide member becomes worn, the bolts can be removed and said member adjusted toward the toe 18 of the frog to bring the engaging face of said member closer to the running line of the frog and thus compensate for wear.

As previously stated, the central portion of the guard members diverge from the wing rails so that the wheel, in passing from the toe toward the point of the frog, will be gradually forced to its clearing position of the point and thus prevent the guard member and frog from receiving a sudden strain or shock.

Having thus described my invention, what I claim as new and desire to secure by Letters Patent is:

1. A railway frog comprising a frog point, wing rails, and guard members comprising webs projecting upwardly from bases and having portions which extend over the heads of the wing rails adjacent the point of the frog; substantially as described.

2. A railway frog comprising a frog point, wing rails, and guard members having heads and bases which rest on the heads and bases of the wing rails adjacent the point of the frog, and means for securing said guard members in position; substantially as described.

3. A railway frog comprising a frog point,

wing rails, and guard members of uniform shape and size adapted to be interchanged with each other, and each consisting of a base, web and a head which extends over the head of the wing rail with which it co-operates; substantially as described.

4. A railway frog comprising a frog point, wing rails, and guard members each of which has a central straight portion, and flared ends, one end of each guard member extending parallel with one face of the frog point, and spacing blocks interposed between the guard members and the wing rails at the toe end of the frog; substantially as described.

5. A railway frog, comprising a frog point, wing rails, and guard members which are so constructed that they can be moved longitudinally of the frog when their engaging faces have become worn to bring said engaging faces closer to the running lines of the frog and thus compensate for wear; substantially as described.

6. A railway frog comprising a frog point, wing rails, and guard members of uniform shape in cross section throughout their length and each consisting of a straight portion which is spaced away from the wing rails, and a flared portion which rests on the head of the wing rail adjacent the point of the frog; substantially as described.

7. As an article of manufacture, a guard member for a railway frog comprising a casting having a web provided at its upper end with a head which is adapted to project slightly over the head of one of the wing rails of the frog, and a base which is adapted to rest on the base of said wing rail; substantially as described.

8. As an article of manufacture, a guard member for a railway frog consisting of a casting having a web provided at its upper end with a head which is adapted to project slightly over the head of one of the wing rails of the frog, said casting having laterally projecting extensions provided with openings to receive fastening devices; substantially as described.

In testimony whereof, I hereunto affix my signature, in the presence of two witnesses, this third day of August, 1906.

ROBERT E. EINSTEIN.
